US0D1042137S

(12) **United States Design Patent** (10) Patent No.: **US D1,042,137 S**
(45) Date of Patent: ** Sep. 17, 2024

(54) **CONTAINER CAP**

(71) Applicant: **Mary Kay Inc.**, Addison, TX (US)

(72) Inventors: **Priscilla Ober**, Addison, TX (US);
Jenny DeMarco Staab, Addison, TX (US);
Iwona Waluk, Addison, TX (US)

(73) Assignee: **MARY KAY INC.**, Addison, TX (US)

(**) Term: **15 Years**

(21) Appl. No.: **29/687,726**

(22) Filed: **Apr. 15, 2019**

(51) LOC (14) Cl. **09-07**

(52) U.S. Cl.

USPC **D9/449**; D9/503

(57) **CLAIM**

The ornamental design for a container cap, as shown and described.

DESCRIPTION

FIG. 1 is a top perspective view of a container cap, with the circle lines on the top surface of the cap and the "Mary Kay" logos illustrated in dashed lines;

FIG. 2 is a front view of the container cap shown in FIG. 1;
FIG. 3 is a back view of the container cap shown in FIG. 1;
FIG. 4 is a left side view of the container cap shown in FIG. 1;

FIG. 5 is a right side view of the container cap shown in FIG. 1;

FIG. 6 is a top view of the container cap shown in FIG. 1;
and,

FIG. 7 is a bottom view of the container cap shown in FIG. 1.

The dashed lines in FIGS. 1-7 are included for the purpose of illustrating portions of the container cap that form no part of the claimed design.

1 Claim, 7 Drawing Sheets
